United States Patent Office

Des. 224,001
Patented June 27, 1972

224,001

SUBMERGIBLE SEA ROOM

William Barkley, 3847 Underwood Drive 3,
San Jose, Calif. 95117

Filed Nov. 19, 1970, Ser. No. 26,074

Term of patent 14 years

Int. Cl. D25—03

U.S. Cl. D13—1

FIG. 1 is a perspective view of the submersible sea room showing my new design.

FIG. 2 is a side elevation thereof.

FIG. 3 is a front elevation thereof.

FIG. 4 is a side elevation of the side opposite from that shown in FIG. 2.

FIG. 5 is a rear elevation thereof.

FIG. 6 is a top plan view thereof.

FIG. 7 is a bottom plan view thereof.

I claim:

The ornamental design for a submersible sea room, as shown.
